UNITED STATES PATENT OFFICE.

ELMER A. WURTZ, OF BARBERTON, OHIO.

STEAM GENERATOR AND REGULATOR FOR TURBINES.

1,014,797.

Specification of Letters Patent. Patented Jan. 16, 1912.

Application filed June 28, 1909, Serial No. 504,813. Renewed June 19, 1911. Serial No. 634,111.

To all whom it may concern:

Be it known that I, ELMER A. WURTZ, a citizen of the United States, residing at Barberton, in the county of Summit and State of Ohio, have invented certain new and useful Improvements in Steam Generators and Regulators for Turbines; and I do declare the following to be a full, clear, and exact description of the invention, such as will enable others skilled in the art to which it appertains to make and use the same.

This invention relates to a steam generator and regulator for turbines.

One object of the present invention is to provide means for generating the steam with a less consumption of fuel than has heretofore been possible.

A further object of the invention is to provide means for regulating the pressure of the steam in the boiler, or for keeping the pressure within certain limits, so that the turbine will operate at an approximately constant speed.

With these and other objects in view the invention consists of certain novel features of construction, combination and arrangement of parts as will be more fully described and particularly pointed out in the appended claims.

In the accompanying drawings, Figure 1 is a diagrammatic view illustrating the application of the device to a steam turbine, and Fig. 2 is an enlarged sectional view of the steam cut-off valve.

Referring to the drawings for a more particular description of the invention, 1 indicates the steam turbine which is only conventionally shown and which may be of any ordinary type, 2 the steam boiler, 3 the water gate thereof, 4 the steam supply pipe between the dome of the boiler and the turbine and 5 the fuel supply tank, the fuel in the present instance being gasoline.

In carrying out the invention an air pipe, 6, communicates with the end of the supply pipe, 4, adjacent the turbine and after extending around one side of the latter leads to the tank, 5. This pipe is provided at a point near the turbine with an enlargement, 7, forming an air chamber and also at a point near the air chamber with an exhaust pipe, 8, provided with a valve, 9. The portion, 10, of the air pipe which extends between the enlargement, 7, and the tank, 5, is provided with the piston chamber, 11,

and at a point nearer the tank with the valve, 12. An air piston, 13, is reciprocatorily mounted in the air chamber, 11, and is actuated by an eccentric, 14, on the turbine shaft, 15. A water supply pipe comprising the upper portion, 16 and the lower portion, 17, extends from the lower end of the boiler, 2, to a point somewhat beyond the lower end of the gasoline tank. The lower end of this pipe, 17, may be connected with a source of water supply in any desired manner. A piston casing, 18, is arranged at the junction of the inner and outer portions, 16 and 17, of the water supply pipe, in which is mounted the piston, 19, which is also operated by a cam on the turbine shaft, 15. The lower portion, 17, of this pipe is provided with the check valve, 20, and at a point above the check valve, with the manually operated valve, 21, while the upper portion thereof is provided with a manually operated valve, 22, and at a point above the latter with a check valve, 23.

The lower end of the boiler, 2, is provided with the combustion chamber, 24, which may be of any suitable form and in the lower end of which fits or extends the upper end of the fuel and air supply pipe, 25, the lower end of which communicates with the upper end of the tank, 5, and is provided with the manually operated valve, 26. A shield, 27, incloses the upper end of the pipe, 25. A pipe, 28, extends from the water supply pipe at the junction of the upper and lower portions 16 and 17, thereof, to the pipe 25 at a point somewhat beneath the lower end of the combustion chamber, 24. The end of this pipe, immediately adjacent the pipe 25, is provided with a manually operated valve, 29, while the opposite end is provided with a check valve, 30, and at a point somewhat nearer the water supply pipe with a manually operated valve, 31. The first mentioned end of the pipe 28, is also provided with a by-pass 32, which is also equipped with a manually operated valve, 33.

The pipe, 25, is provided at one side and at a point somewhat beneath the lower end of the combustion chamber, 24 with the piston chamber, 34, in which is mounted the piston, 35. This piston is provided with a contact, 36, the outer end, 37, of which is normally held in contact or engagement with the contact, 38, by means of the spring, 39, which is disposed within the piston cham-

ber, 34. A solenoid 40 is arranged beneath the piston chamber 34, and is connected with the contact, 38 by the conductor, 41. The opposite end of the solenoid is connected with the battery, 42, or other source of current by the wire, 43. A conductor, 44, leads from the opposite side of the battery and is provided with the electrode, 45, which extends into the upper end of the shield, 27, at a point immediately above the upper end of the fuel supply pipe, 25, and being disposed adjacent to a second electrode, 46, connected with the contact, 36, by the conductor, 47. A cut-off valve, 48, is pivotally mounted upon a cylindrical extension, 49, formed at the lower end of the pipe, 25, and is provided with the armature, 50.

In the operation of the device, air is pumped into the pipe, 6, and into the tank, 5, by the piston, 13. As the air passes into the tank, 5, which is filled with gasolene, it mixes with the gasolene and passes to the upper end of the supply pipe, 25, where it is ignited by the spark which jumps across the electrodes, 45 and 46. To cause the current to pass between the electrodes 45 and 46 when the circuit is closed, an induction coil I is arranged in the circuit, of which coil i is the primary and i' the secondary.

After this air and gasolene mixture is thus ignited the products pass through the combustion chamber into the boiler, 2, and to the upper end of the latter, and in doing so all heat is absorbed by the water in the boiler which eventually turns into steam. When the water in the boiler becomes too low the manually operated valves 22 and 29 are closed while the valves 31 and 33 are opened. When the steam in the boiler reaches its high pressure limit, the piston, 35, is forced outwardly against the action of the spring, 39, which disengages the contact, 36, with the contact, 38, when the circuit is broken and the solenoid demagnetized which permits the armature, 50, to drop when the valve, 48, closes and cuts off further supply of the heating fuel or the air and gasolene mixture to the combustion chamber. After the steam pressure falls below the maximum or highest limit, the piston, 35, is returned to normal position by the action of the spring, 39, which again brings the contact 36, into engagement with the contact, 38, which closes the circuit and energizes the solenoid. When the solenoid is thus energized, the armature 50 is again retracted and the valve, 48, opened which permits the fuel to again pass through the pipe, 25. The tank 5 is charged with air

as fast as it is utilized, by the piston 13 which pumps air through the pipe 10 to the tank. However, should the piston supply air to the tank faster than it is used, when the resulting pressure exerted against the face 53 of the cut-off valve 51 arranged in

pipe 6 exceeds the steam pressure exerted against the face 52 of said valve the valve is moved into steam cut-off position. The valve 12 in pipe 10 is then closed and valve 9 opened, when the air in pipe 6 is allowed to escape through the pipe 8 and the valve 51 is permitted to return to normal position, when steam again passes to the turbine. When the water becomes low in the boiler, it is recharged by closing valves 22 and 29 and opening valves 31 and 33. The piston, 19, then draws water through the lower portion, 17, of the water supply pipe and forces it through the pipe, 28 and the by-pass pipe 32, into the combustion chamber of the boiler. After the water reaches the proper height in the boiler and the engine is again running, the valve, 33, may be closed and the valve, 29, may be opened so that the water will pass through the upper end of the supply pipe, 25. This is done to keep the supply pipe filled with water which trickles down through the pipe, 25, into the gasolene tank, 5, as each bubble of air and gasolene passes upward through the water in the same pipe, thus keeping the upper end of the tank and the entire supply pipe filled with water so that the air and gasolene bubbles may rise.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention.

Having thus described my invention, what I claim is:

1. A steam generator for turbines, engines and heating systems, comprising a boiler, a fuel supply device communicating with the lower end thereof, an igniting device for the fuel, a cut-off valve for the fuel, and means for throwing the igniting device out of operation when the maximum steam pressure is reached.

2. A steam generator for turbines, engines and heating systems comprising a boiler, a fuel supply device communicating with the lower end thereof, an electro-magnetic device for igniting the fuel, a cut-off valve for the fuel, normally held open by the igniting device, and means for breaking the circuit through the igniting device when the maximum pressure of the steam is reached to permit the cut-off valve to close.

3. A steam generator for turbines, engines, and heating systems, comprising a steam boiler, a fuel supply device involving a gasolene tank communicating therewith, means driven by the turbine for forcing a charge of air through the tank to mix with

the gasoline, connections including a piston driven by the turbine for continuously passing water through the upper end of the fuel supply device, an igniting device for the fuel, a cut-off valve for the fuel, means for normally holding the cut-off valve in open position to permit the air and gasoline mixture to pass into the boiler, and means to throw the valve holding means out of operation to provide for the release of the valve when the maximum steam pressure in the boiler has been reached.

4. A steam generator for turbines, engines and heating systems, comprising a steam boiler, a fuel supply device involving a gasoline tank communicating therewith, means driven by the turbine for forcing a charge of air through the tank to mix with the gasoline, connections including a piston driven by the turbine for continuously passing water through the upper end of the fuel supply device, an igniting device for the fuel, a pivoted fuel cut-off valve, electro-magnetic means for normally holding the valve in open position, and means for breaking the circuit through the electro-magnetic means when the maximum pressure of the steam in the boiler is reached.

5. A steam generator for turbines, engines and heating systems, comprising a steam boiler, a fuel supply device involving a gasoline tank communicating therewith, means driven by the turbine for forcing a charge of air through the tank to mix with the gasoline, connections including a piston driven by the turbine for continuously passing water through the upper end of the fuel supply device, an igniting device for the fuel, a fuel cut-off valve pivoted to the fuel supply device and provided with an armature and electro-magnetic means including a solenoid for attracting the armature of the valve in order to hold the latter in open position when the circuit is closed through the igniting device and solenoid, and means for breaking the circuit through the solenoid and igniting device when the maximum steam pressure in the boiler is reached.

In testimony whereof I have hereunto set my hand in presence of two subscribing witnesses.

ELMER A. WURTZ.
